ELECTRODE MOUNT

Theodore A. Sternberg, Newark, N. J., assignor,
by mesne assignments, to Radio Corporation of
America, New York, N. Y., a corporation of
Delaware

Application April 6, 1935, Serial No. 15,006

2 Claims. (Cl. 250—27.5)

This invention relates to electron discharge devices employing all-metal envelopes, and is particularly directed to improvements in the electrode supporting means.

- 5 In radio tubes with metal envelopes enclosing an electrode assembly it has been found desirable to assemble some, at least, of the electrodes into a unitary structure which is afterwards positioned inside the envelope. In one form of all-
10 metal tube the envelope comprises a metallic cup-shaped member and a metal disc or header welded or brazed gas-tight to the lip or rim of the cup shaped member, and the electrode assembly is supported upon the header.
15 It is an object of my invention to support the electrode assembly very rigidly on the header by supporting means that is rugged and easy to manufacture.

A full understanding of my invention may be had by referring to the accompanying drawing in which Figure 1 is a perspective view of details of my invention; and Figure 2 is a partly sectional view of a tube embodying my invention.

As shown in Figure 2, the tube has a metal envelope comprising a cup-shaped member 1 and a flanged metal disc 2 secured gas tight to the flared rim of the cup-shaped member. Mounted inside the envelope is a unitary electrode assembly which, merely as an example, is shown 20 as a grid electrode 3 and a cathode 4 held between insulating end spacers 5 and an anode 6, shown as separately supported upon the header, but which may also be a part of the unitary electrode assembly if desired.

25 In accordance with my invention I prefer, as best shown in Figure 1, to support the unitary electrode assembly on a U-shaped bracket secured to the header and preferably made from a single piece of heavy wire or round stock bent to form 30 a bracket having supporting side rods 7 and 8 which carry the spacers 5. Side rods 7 and 8 are joined at their lower ends by a horizontal portion of the wire stock which is suitably secured, as by welding, to the header. To lend rigidity 35 to the electrode supporting means I prefer to extend the bearing surface between the bracket and the header by bending the horizontal portion of the wire stock perpendicularly lateral to the plane thru the side rods to form a curved 40 footing member 9. With a wide footing as thus

formed, the side rods are effectively braced against tilting in any direction. That is, by securing the rods to the header at several points along portion 9 as by spot welding, the upstanding ends 7 and 8 are rigidly and accurately fixed 5 in a plane perpendicular to the surface of the header, and by virtue of the laterally extending loop 9 the side rods 7 and 8 are stably anchored in a fixed vertical plane.

A tube constructed in accordance with my invention may be assembled very easily and conveniently by securing the electrode assembly, as best shown in Figure 2, to the upper ends of side rods 7 and 8, the assembly inserted in the open end of the cup-shaped portion 1 of the envelope, and the rim of said portion and the edge of the header sealed together by welding or brazing.

It will be obvious to those skilled in the art that a tube constructed in accordance with my invention affords a rigid and accurate positioning and supporting means for the electrode assembly within the envelope. It will be obvious, further, to those skilled in the art that various modifications may be made in my invention 25 without departing from the scope thereof. It is accordingly desired that my invention be limited only by the prior art and by the accompanying claims.

30 I claim:

1. In a discharge device, an envelope with a flat end portion, an electrode assembly of the unit mount construction, supporting means for said assembly comprising two upstanding parallel rods joined at their lower ends by an integral portion of the rods to said flat portion of the envelope, and means for securing said electrode assembly to the upper ends of said rods. 35

2. In a discharge device, an envelope with a flat end portion, electrode supporting means comprising a U-shaped rod with parallel upstanding portions and a horizontal tying portion at the lower ends of said upstanding portions, said tying portion being laterally bent in a plane 40 normal to the plane thru said upstanding portions and secured to the flat portion of said envelope, and an electrode secured to the upstanding portions of said rod. 45
